Primary Examiner — Jack Reickel*Assistant Examiner* — Rene H. Kadoo(74) *Attorney, Agent, or Firm* — Luedeka Neely, P.C.(57) **CLAIM**

The ornamental design for a cross brace for a tabletop, as shown and described.

DESCRIPTION

FIG. 1 is a perspective view of a cross brace for a tabletop showing my new design;

FIG. 2 is a side elevation view thereof, the opposite side being identical;

FIG. 3 is a top plan view thereof;

FIG. 4 is a bottom plan view thereof; and,

FIG. 5 is an end elevation view thereof, the opposite end being identical.
